MEAT GRINDER

Henry J. Talge, Kansas City, Mo., and James B. Aberer,
Mission, Kans., assignors to John C. Hockery, Kansas
City, Mo., trustee

Application March 11, 1959, Serial No. 54,928

Term of patent 14 years

(Cl. D89—1)

Fig. 1 is a top plan view of a meat grinder embodying our new design;

Fig. 2 is a front elevational view of the same;

Fig. 3 is a side elevational view of same; and

Fig. 4 is a side elevational view showing same from the opposite side.

We claim:

The ornamental design for a meat grinder, as shown.
